The Lowell Manufacturing Company, of same place.

Letters Patent No. 1922-Dated March 15th, 1864.

Design for a Carpet Pattern.

The schedule referred to in these Letters Patent and making part of the same.

To all whom it may concern:

Is it known that Elmer J. Key, of Lowell, in the County of Middlesex and State of Massachusetts, have originated and designed an improvement in a pattern for carpets or other fabrics, of which the following is a full, clear and exact description, reference being had to the accompanying drawings making part of this specification.

The specification refers to that part of the drawings enclosed by blue lines.

The improvement consists in substituting the block A, which is surrounded by fine mottled work, and the figures 1, 2, 3, 4, 5, 6, which are halves of figures similar to A, for the figures bearing corresponding letters and numbers, in design designated Application A, for which Letters patent were granted bearing date of February Sixteenth, A. D. one thousand eight hundred and sixty four.

The remaining parts of the design are copied from design designated Application A, as above.

The colors employed for the different portions of the design may be varied to suit the taste and wish of the manufacturer.

~ Claim. ~

What I claim as my invention and desire to secure by Letters Patent is, The improvement in a design or pattern for carpets or other fabrics, herein set forth.
